METHOD OF MAKING SLIDE FASTENERS

Alexander Konoff, Brooklyn, N. Y., assignor, by
mesne assignments, to Conmar Products Cor-
poration, Bayonne, N. J., a corporation of New
Jersey

Application July 14, 1934, Serial No. 735,131

7 Claims.

(Cl. 153—1)

This invention relates to method of making slide fasteners.

In accordance with conventional practice, slide fastener elements are applied to and secured upon beaded tapes, thereby forming what are commonly known as the stringers of the slide fastener. These stringers are subsequently sewed to the edges of the article on which the fastener is to be used. This practice is subject to important disadvantages, as in the case where the fastener is employed on leather articles, for example, wallets, brief-cases, and heavier luggage, because the fabric tape is not nearly as strong as the leather wall of the article and becomes the weakest link or element in the article. The tape is subjected to considerable wear, and frequently wears out before the article has lived its useful life. In some cases the use of a tape is disadvantageous for other reasons, say when a light-weight fastener is applied to a thin light fabric, as in a lady's garment, for the tape may be objectionable in appearance, texture or color. In every case a certain amount of skilled labor is required to properly attach the stringers to the article.

The object of my invention is to generally overcome the foregoing difficulties and to eliminate the use of a tape between the article wall and the fastener element, and to instead provide a suitable method for securing the fastener elements in properly spaced and properly aligned relation directly to the edge of the article wall.

To the accomplishment of the foregoing and other objects which will hereinafter appear, my invention consists in the products and method steps and their relation one to another, as hereinafter are more particularly described in the specification and sought to be defined in the claims. The specification is accompanied by a drawing, in which:

Fig. 1 is a plan view of a strip of fastener elements preparatory for subsequent mounting;

Fig. 2 is a side elevation of the same with some of the elements removed;

Fig. 3 is a section taken in the plane of the line 3—3 of Fig. 2;

Fig. 4 is a section through clamping apparatus, and illustrates the mode of mounting the elements on the wall of an article;

Fig. 5 is a similar view showing the completion of the clamping operation; and

Fig. 6 is a perspective view of an article embodying my invention.

Referring to the drawing and more particularly to Figs. 1, 2, and 3, the fastener elements E are

of conventional type and comprise a head 12 and jaws 14 and 16 formed integrally therewith. The head is provided with appropriate mating or interlocking means exemplified in the present case by a recess 18 at one side of the head and a projection 20 at the opposite side of the head.

The elements E are temporarily mounted on a strip S of preferably destructible material, such as cardboard or like material. The elements are mounted on the strip in proper alignment and in uniformly spaced relation, with a spacing equal to that employed in the finished fastener. The strip is arranged transversely of the fastener elements and extends between the open jaws of the elements, as is best shown in Fig. 3. In order to maintain the elements accurately in the desired relation, I prefer to preliminarily notch the strip S with a series of notches 22 disposed at the opposite edges of the strip. These notches receive the jaws of the elements tightly and aid greatly in holding the elements in desired relation without necessitating undue thickness of the cardboard strip. The elements are most simply applied to the strip by pressing the same toward the strip jaws first, the jaws then entering the notches of the cardboard. This operation may be performed by the machine which forms the elements. The notches 22 may all be formed in advance or, more preferably, may be cut step by step by the same press or punch that feeds the elements into the strip.

It will be understood, of course, that the temporary strips of elements are formed at the fastener factory and are then shipped to the manufacturer of the article for application thereto. The strips may be formed of desired length, just as is now the case with tape stringers, or they may be shipped in continuous length and severed to desired length by the article manufacturer. Most preferably, the elements are applied to a continuous strip but in spaced groups, thus facilitating separation of the groups.

The manufacturer is provided with clamping mechanism such as is shown in Figs. 4 and 5 of the drawing. This clamping mechanism comprises an elongated stationary jaw 30 mounted on a base 32, and a movable jaw 34 pivoted on the stationary jaw by a shaft 36. It will be understood that Figs. 4 and 5 are sections taken across the jaws which are greatly elongated in a direction transverse to the drawing, being made of sufficient length to receive a complete strip of elements of maximum normally used length.

The movable jaw 34 is actuated by one or more arms 38 (preferably two, one near each end

of the jaw), arm 38 resting upon and being actuated by a cam 40. One or more cams 40, corresponding to the number of arms 38, are mounted on a cam shaft 42 which is actuated by a lever 44. It will be manifest that oscillation of lever 44 causes cam 40 to elevate arm 38 and to thereby close jaws 30 and 34.

Cam 40 comprises three sections 46, 48, and 50 of progressively increasing radius. With lever 44 in its rearward position and arm 38 resting against the first portion 46 of the cam, the jaws are fully open and readily receive therebetween a strip of fastener elements. By then moving lever 44 to the position shown in Fig. 4, the jaws 15 are partially though only slightly closed by the cam portion 48, the movement being sufficient to squeeze the jaws 14 and 16 of the elements E and to lock the same securely in place. The 20 destructive cardboard strip S is then pulled from the fastener elements, the latter being held tightly in original alignment by the partially closed clamping jaws. The wall 52 of the article is then placed between the open jaws 14 and 16 of the row of elements, as is shown in Fig. 4, whereupon 25 lever 44 is pulled forwardly to the position shown in Fig. 5, at which time the portion 50 of the cam causes the clamping jaws to move together and to clamp the elements securely upon the article. Lever 44 is then moved backwardly and 30 the article wall 52 removed. A guide table 54 may be provided on which to rest the material 52, or, if desired, the lower jaw 30 may be projected forwardly or widened to act as a table.

It will be noted that jaws 30 and 34 are preferably recessed at 56 to accurately receive the closed elements, as is shown in Fig. 5, the recesses 35 56 being defined at the forward edge by shoulders 58, which shoulders help align and accurately locate the elements during the clamping operation, as is best illustrated in Fig. 4.

The edge of the article wall 52 is preferably beaded to form a bead 60. This may be done in any desired manner, and in the present case the edge is simply curled and stitched. The 45 material of the wall depends upon the nature of the article, and in the present case, may be assumed to be leather.

It is desirable to hold the bead tightly in the jaws of the elements when closing the same. For 50 this purpose the apparatus preferably includes an elongated pusher bar 70 pivoted at 72 on stationary bearing pedestals 74. The lower part of the pusher bar 70 is provided with a large number of pusher fingers 76, spaced at the spacing 55 of the fastener elements E, and dimensioned to fit therebetween. The pusher bar is urged inwardly by pulling operating lever or handle 78 forwardly to the position shown. Upon actuation of lever 44 the elements are closed as shown in 60 Fig. 5, the upper jaws of the elements coming down between the fingers 76 of the pusher bar.

In Fig. 6 I show one of a large number of typical articles to which my invention may be applied. The luggage bag 62 is made of leather or other suitable material, and is closed by a 65 slide fastener 64 operated by a slide 66. The fastener elements are secured directly to the material of bag 62, preferably before assembling the parts of the bag, and no fabric tape is required or used. The bag is thereby improved in durability and appearance.

It is believed that the temporary stringer or strip of elements of my invention, as well as the method of forming the same and of applying the elements directly to the edge of an article wall 75

without using an intermediate tape, and also the many advantages thereof, will be apparent from the foregoing detailed description. It will also be apparent that while I have shown and described my invention in preferred form, many changes and modifications may be made, without departing from the spirit of the invention, defined in the following claims.

I claim:

1. In the manufacture of a temporary stringer 10 for a slide fastener, the method which includes temporarily mounting a series of open-jawed elements in properly uniformly spaced and aligned relation on a strip of cardboard or like material with the open jaws of the elements astride the 15 strip with a snug fit capable of holding said elements in place on the strip during normal handling of the strip preparatory to permanently mounting the elements on some other carrier, said elements having interlockable head portions 20 each including a projection and a recess, said head portions being disposed remote from the strip with the strip extending transversely of the elements between the jaws, the jaws of each element bearing against opposite edges of the strip. 25

2. In the manufacture of a temporary stringer for a slide fastener, the method which includes notching the edges of a destructible strip of cardboard or like material at the proper uniform spacing for the fastener elements to interlock 30 properly when in use, and mounting a series of open-jawed elements in aligned relation on said cardboard strip with the open jaws of the elements received in the notches of the strip, said elements having interlockable head portions each 35 including a projection and a recess, said head portions being disposed remote from the strip with the strip extending transversely of the elements between the jaws.

3. In the manufacture of an article provided 40 with a slide fastener, the method which includes mounting a series of open-jawed elements in properly uniformly spaced and aligned relation on a destructible strip of material, said elements having head portions with projections and recesses 45 adapted to interlock, simultaneously clamping the exteriors of the elements and slightly compressing the jaws, placing the edge of an article wall between the jaws and thereupon further clamping the jaws in order to close the same directly 50 upon the edge of the article wall without the use of any conventional tape intermediate the article wall and the fastener elements.

4. In the manufacture of an article provided 55 with a slide fastener, the method which includes mounting a series of the elements in properly uniformly spaced and aligned relation on a strip of cardboard or like material with the jaws of the elements astride the strip, said elements having head portions with projections and recesses 60 adapted to interlock, the strip extending transversely of the elements between the jaws, clamping the exteriors of the elements and slightly compressing the jaws, removing the cardboard strip from between the jaws, placing the edge of 65 an article wall between the jaws and thereupon further clamping the jaws in order to close the same directly upon the edge of the article wall without the use of any conventional tape intermediate the article wall and the fastener elements. 70

5. In the manufacture of an article provided 75 with a slide fastener, the method which includes notching a destructible strip of cardboard or like material at the proper uniform spacing for the

fastener elements in use, mounting a series of the elements in properly aligned relation on said cardboard strip without closing the jaws of the elements, said elements having head portions with projections and recesses adapted to interlock, placing the edge of an article wall between the jaws and thereupon clamping the jaws in order to close the same directly upon the edge of the article wall without the use of any conventional tape intermediate the article wall and the fastener elements.

6. In the manufacture of an article provided with a slide fastener, the method which includes notching the edges of a destructible strip of cardboard or like material at the proper uniform spacing for the fastener elements in use, mounting a series of the elements in properly aligned relation on said cardboard strip with the open jaws of the elements received in the notches of the strip, said elements having head portions with projections and recesses adapted to interlock, the strip extending transversely of the elements between the jaws, simultaneously clamping the

exteriors of the elements and slightly compressing the jaws, removing the cardboard strip from between the jaws, placing the edge of an article wall between the jaws and thereupon further clamping the jaws in order to close the same directly upon the edge of the article wall without the use of any conventional tape intermediate the article wall and the fastener elements.

7. In the manufacture of a slide fastener, the method which includes mounting a series of open-jawed elements in properly uniformly spaced and aligned relation on a mounting strip, said elements having head portions with projections and recesses adapted to interlock, simultaneously clamping the exteriors of the elements and slightly compressing the jaws thereof in order to hold the elements in proper relation, removing the mounting strip, then placing the edge of a flexible piece of material between the jaws, and thereupon further clamping the jaws in order to simultaneously close the same upon the aforesaid edge.
